UNITED STATES PATENT OFFICE.

DAVID GENESE, DECEASED, LATE OF BALTIMORE, MARYLAND; BY NORRIS GENESE, OF BALTIMORE, MARYLAND, ADMINISTRATOR, ASSIGNOR OF ONE-HALF TO WILLIAM H. OREM, OF BALTIMORE, MARYLAND.

PROCESS FOR TREATMENT OF PAPER.

No Drawing. Original application filed August 18, 1926, Serial No. 130,070. Divided and this application filed August 31, 1927. Serial No. 216,772.

This invention relates to the process for making modified fibrous stock and is disclosed in pending application Serial No. 130,070, filed August 18, 1926, of which this application is a division and applied for in the name of the inventor, David Genese, deceased, by Norris L. Genese, administrator, the bottle cap forming the subject-matter of said pending application being one of the specific utilizations of fibrous stock modified according to the provisions of the present process.

This process involves the treatment of paper, cardboard, or other fibrous stock so as to enhance to a remarkable degree the qualities of resiliency and shrinkability.

The process consists in thoroughly wetting ordinary paper stock or cardboard with a solution of boracic acid, or the like, and then drying it, preferably with the application of heat. Under this treatment, changes, either chemical or physical, take place in the stock, so that it acquires the increased modulus of elasticity, and shrinkability, above referred to.

No particular apparatus is prescribed for carrying out the process, but it may be performed by passing fibrous stock through a

bath of concentrated aqueous solution of boracic acid, and then drying it between heated rollers, the temperature of which may be high enough to evaporate the water in the form of steam.

The stock thus modified is suitable for general application wherever paper or cardboard of great elasticity and shrinkability is desired. It lends itself particularly to the manufacture of molded articles, such as the lids of receptacles which fit with a gripping pressure that is not materially weakened by repeated removal and replacement of the lid. In the molding of such articles, the modified stock is first wetted and again dried.

What it is desired to claim is:

The process of modifying paper to increase the elasticity and shrinkability thereof, comprising moistening the paper with a concentrated solution of boracic acid, and drying the paper under heat and pressure.

In testimony whereof I have hereunto set my hand.

NORRIS GENESE,
Administrator of the Estate of David Genese, Deceased.
